UNITED STATES PATENT OFFICE.

WALTER A. ROWE, OF TIFFIN, OHIO.

LAVATORY.

Application filed August 9, 1924. Serial No. 731,121.

The present invention relates to lavatories, and more particularly to lavatories made of clay or other plastic material.

An important feature of this invention is the combination of a solid or single wall basin and a support at the back thereof for supporting the basin and preventing it from sagging when the lavatory structure is in the green state and during firing.

Another feature of the invention is the cast-in overflow at the back of the basin.

A further feature of the invention is the provision of recesses and holes for the accommodation of fittings.

Additional features of the invention will be apparent from the following description:

In the drawings,

Figure 1 is a view partly in plan and partly in horizontal section of a preferred form of lavatory embodying my invention;

Figure 2 is an inverted plan view of the lavatory;

Figure 3 is a vertical section on the line III—III of Figure 1;

Figure 4 is a sectional view of the lavatory on the line IV—IV of Figure 3, and

Figure 5 is a vertical section on the line V—V of Figure 1.

The basin 2 of the lavatory from the apron 3 down to the waste outlet 4 is formed solid except at the back thereof where a cast-in overflow passage 5 is provided. The bowl is surrounded by the usual horizontal ledge or slab 6 and extending vertically from the rear edge thereof is a back 7 having a thickened hollow rim 8. It will be apparent that the back 7 may or may not be provided. The apron 3 is also formed hollow.

The solid or single wall portion of the basin is produced by the method known in the art as double casting, that is to say, the walls of the plaster of Paris mold are placed close enough together to draw the moisture out of the clay so that the clay is cast solid between them. However, at the back of the basin the walls of the mold are placed at a distance apart such that the clay is left in a liquid state in the central portion of the molded wall and can be drawn out to form the outlet passage 5. This method of casting is what is known as single or hollow casting. In order to remove this liquid clay, the basin is tilted at an angle sufficient to insure proper drainage, and an opening α is formed at an upper corner of the basin, and a drain opening d , as shown in Figure 4 of the draw-

ings is provided. Thereupon the liquid clay drains from all of the cavities to the drain opening. These holes a and d are then plugged up and the lavatory is set on its back to dry from the green state and is afterward fired, still resting on its back.

In order to support the basin while being dried from the green state and also during firing, I cast the lavatory with a supporting arm 9 at the central portion of the back wall of the basin. This supporting arm is flush with the back 7 and extends downwardly from said back and from the portion of the apron 3 at the rear of the lavatory. The lower end of the arm is in substantially the same horizontal plane as the lower surface of the basin at the waste outlet 4. Formed in this supporting arm and opening out through the rear face thereof is a relatively large recess 10. Communicating with this recess are two aligned holes 11 and 12, the hole 11 extending through the ledge 6 at the rear of the basin and centrally thereof and the hole 12 extending through the lower portion of the arm 9. These holes are provided primarily for the reception of the operating rod for the usual pop-up valve for controlling the waste outlet 4. It will be noted that these holes are accessible from the back of the lavatory through the recess 10, this being an important feature in that it enables a plumber to readily obtain access to these holes for making his fittings.

Extending through the ledge 6 at the back of the lavatory and at opposite sides of the supporting arm 9 are the usual cock-holes 13 and 14 for the hot and cold water pipes. These holes may be of uniform diameter throughout or may be tapered at one side as indicated respectively at 13' and 14' in the drawings to provide the desired play for the cock connections. The under surface of the lavatory is counter sunk around these holes for the reception of the fittings, as indicated by the reference numeral 15. Transverse openings 16 extend through the supporting arm 9 and communicate with the recess 10 and with the counter sunk recesses 15. When a universal fitting is used, the pipe for the common cold and hot water spigot comes up through the hole 12 and the holes 16 are utilized for the passage of the operating mechanism from the hot and cold water buttons to the valve which is located in the recess 10. These hot and cold water buttons project up through the cock-holes 13 and 14.

The waste outlet 4 and the holes 16 in the supporting arm 9 and the hole 17 leading from the basin to the overflow passage 5 are cut when the clay is green. The cock-holes 13 and 14 however are formed by cores in the mold.

It has heretofore been customary in the art to attempt to support the lavatory during firing by the use of a separate prop or block. This, however, has not been satisfactory, while the integral support or arm 8 forms an efficient support facilitating handling.

While I have shown and described a preferred embodiment of my invention, it will be understood that changes may be made in the details of construction without departing from the spirit of the invention or scope of the appended claims.

20 I claim:

1. A lavatory comprising an integral structure having a bowl and a vertical back, both the bowl and the back having an integral hollow rim extending thereabout, and 25 an integral support under the back and at the rear of the bowl having its face flush with the rear face of the back, an integral overflow passage being provided between the bowl and the support, substantially as described.

2. A lavatory comprising an integral structure having a bowl and a vertical back, both the bowl and the back having an integral hollow rim extending thereabout, and 35 an integral support under the back and at the rear of the bowl having its face flush with the rear face of the back, an integral overflow passage being provided between the bowl and the support, said support having 40 passages therein for the reception of plumbing fixtures, said passages being separate from the overflow passage, substantially as described.

3. A lavatory including a bowl and a slab 45 at the top of the bowl, a support at the back of the bowl of a height substantially co-extensive with the depth of the bowl and integral therewith, said support having a horizontally opening cavity therein for the reception 50 of plumbing fixtures, substantially as described.

4. A lavatory including a bowl and a slab at the top of the bowl, a support at the back of the bowl of a height substantially co-extensive 55 with the depth of the bowl and integral therewith, said support having a horizontally opening cavity therein for the reception of plumbing fixtures, said slab having a plurality of passages therein communicating 60 with the said cavity, substantially as described.

5. A lavatory including a bowl and a slab at the top of the bowl, a support at the back of the bowl of a height substantially co-extensive 65 with the depth of the bowl and integral therewith, said support having a horizontally opening cavity therein for the reception of plumbing fixtures, an overflow passage between the bowl and the support, and a plurality of passages in the slab communicating 70 with the said cavity, substantially as described.

6. A lavatory comprising a bowl, a ledge or shelf at the upper edge of said bowl extending along its back, a support extending rearwardly from the central portion of the back of said bowl for supporting the latter during firing, said support having a recess therein opening through its rear face and holes through its sides communicating with 80 said recess, said recess and holes being adapted to accommodate valve means and valve operating means, and said shelf having a cock-hole therein at each side of said support, the lower face of said shelf being 85 counter sunk around said cock-holes, substantially as described.

7. A lavatory including a bowl and a slab at the top of the bowl, a support at the back of the bowl of a height substantially co-extensive 90 with the depth of the bowl and integral therewith, said support having a horizontally opening cavity therein for the reception of plumbing fixtures, said cavity also having an opening in the bottom thereof, a 95 plurality of passages in the slab communicating with the cavity, and an overflow passage interposed between the support and the bowl and out of communication with the cavity or the passages in the slab, substantially as described.

8. A lavatory having a plurality of fitting-receiving openings, and having a common opening intersecting a plurality of said first mentioned openings and facilitating access 105 thereto, substantially as described.

9. A lavatory comprising a bowl, a ledge or shelf at the upper edge of said bowl extending along its back, a support extending rearwardly from the central portion of the back of said bowl for supporting the latter during firing, said support having a recess therein opening through its rear face and holes through its sides communicating with 110 said recess, said recess and holes being adapted to accommodate valve means and valve operating means, and said shelf having a cock-hole therein at each side of said support, substantially as described.

In testimony whereof I have hereunto set 115 my hand.

WALTER A. ROWE.
